SPIRAL CAM ADJUSTABLE SOCKET WRENCH

Frank C. Peterson, Locona, C. Z.

Application March 14, 1945, Serial No. 582,595

1 Claim. (Cl. 81—128)

1

This invention relates to socket wrenches, and has more particular reference to a wrench of this kind embodying adjustable socket sections which adapt the wrench for turning bolts and nuts of various sizes.

The primary object of the invention is to provide, in a wrench of the above kind, a socket unit which is of simple, durable and compact construction, and in which the adjustable jaws may be readily and conveniently adjusted to suit the size of a nut or the head of a bolt to be turned.

More specific objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a side elevational view of an adjustable socket unit constructed in accordance with the present invention.

Figure 2 is a top plan view thereof.

Figure 3 is a bottom plan view of the same.

Figure 4 is a vertical section taken on line 4—4 of Figure 2.

Figure 5 is a vertical section taken on line 5—5 of Figure 2.

Figure 6 is a horizontal section taken on line 6—6 of Figure 5.

Figure 7 is a top plan view of one of the adjustable socket sections.

Figure 8 is a bottom plan view of the adjusting ring for the adjustable jaws.

Figure 9 is a view similar to Figure 3 illustrating a modification of the socket sections.

Referring in detail to the drawings, the illustrated form of the present socket unit for wrenches includes a circular body 5 formed at one side with an integral depending socket section 6 of segmental form and formed at the top with a central upstanding cylindrical stud 7 provided with a central polygonal socket 8 adapted for snug removable reception of the similarly shaped end portion of an ordinary wrench handle or shank by means of which the unit is turned. As such wrench handles or shanks are conventional and well known in the art, the same is not illustrated herein. The body 5 is provided with two sets of parallel slots therethrough at 9 and 9a, at each side of the integral or fixed socket 6, the slots 9a being radial to the body 5 and the slots 9 being undercut or of dovetail shape in cross sec-

2

tion, as shown in Figures 4 and 5. Slidably disposed against the under side of the body 5 at opposite sides of the socket section 6, are similar adjustable socket sections 10 and 10a which are provided at the top with parallel ribs 11 and 11a. The ribs 11 and 11a of each adjustable socket section snugly slidably fit in the corresponding slots 9 and 9a of each set, so that the adjustable socket sections are adjustable radially of the body 5 relative to each other and the fixed or stationary socket section 6.

The ribs 11a are provided at the top with spiral thread portions 12 that project above the surface of the body 5. Rotatably fitted on the lower portion of the stud 7 is an adjusting ring 13 provided in its under surface with a spiral groove 14 to receive the thread portions 12 of the ribs 11a. Thus, by rotating the ring 13 about the stud 7, the adjustable socket sections 10 and 10a may be radially adjusted toward or away from each other and the stationary socket section 6, depending upon the direction of rotation of said ring 13. Due to the dove-tail form of the slots 9 and ribs 11, the adjustable socket sections are retained in connected relation to the body 5 in all positions of their adjustment, and it is preferred to have the socket sections of similar size so that they will conjointly form a closed socket for reception of the bolt head or nut when the socket sections are in contiguous relation, as shown in Figure 3.

Secured on the upper end portion of the stud 7 is a retaining collar 15 which may be threaded on the stud 7, as shown in Figures 4 and 5, so as to retain the adjusting ring 13 on the stud 7 in a manner to prevent objectionable vertical play of the ring 13 while permitting free manual rotation of the latter. Preferably, the ring 13 is of an outside diameter similar to that of the body 5 and the collar 15 and may have its outer surface knurled or roughened to facilitate gripping and turning the same.

In the embodiment of Figures 1 to 8, inclusive, the socket sections are formed for engagement with hexagonal nuts and bolt heads. However, by forming the inner faces of the socket sections with additional V-shaped grooves 16, a socket of the well known "box" type may be provided to adapt the wrench for engagement with different shapes of nuts and bolt heads and to enable a new purchase on the nut or bolt head under adverse conditions well understood in the art. This is illustrated in Figure 9, wherein the adjustable socket sections are indicated at 10' and

55

10² and the fixed or stationary socket section at 6'.

From the foregoing description, it is believed that the construction and operation, as well as the advantages of the present invention, will be readily understood and appreciated by those skilled in the art. It will be seen that the device is so constructed as to effectively carry out the stated objects of the invention, and it is to be understood that minor changes may be made in details of construction illustrated and described, such as fairly fall within the spirit and scope of the invention as claimed. For instance, all of the jaws may be adjustable, and the number of jaws used may vary.

What I claim is:

An adjustable socket wrench for turning bolts and nuts, comprising a circular body having an integral depending sector-shaped socket section at one side, a pair of radially adjustable sector-shaped socket sections slidably connected to the bottom of the body and disposed at opposite sides of the integral socket section; said body having two sets of slots therethrough with three parallel slots in each set and being provided with an integral central upstanding cylindrical stud formed with a square handle-receiving socket, a set of three ribs on the top of each adjustable socket section slidably engaged in the slots of one set, the intermediate rib of each set being provided on its upper surface with spiral thread portions, the remaining ribs of each set and the slots engaged thereby being of dovetail form, an

adjustable ring rotatable on said stud and provided in its under surface with a spiral thread groove receiving the thread portions of the intermediate ribs of the adjustable socket sections whereby rotation of said ring will effect adjustment of the adjustable socket sections toward or away from each other radially of the body, depending upon the direction of rotation of said ring, the body and the adjusting ring being of the same diameter as the combined socket sections when the adjustable socket sections are fully adjusted toward each other, and a collar secured on the upper end of said stud and rotatably confining said ring against the body with the thread portions of said ribs engaged in the spiral groove of said ring, said collar being of the same diameter as the body and the adjusting ring.
